United States Patent

Des. 240,570
Patented July 20, 1976

240,570

KNITTED SLIPPER

Esther C. Karna, 1996 Camino al los Cerros,
Menlo Park, Calif. 94025

Filed Sept. 12, 1974, Ser. No. 505,589

Term of patent 14 years

Int. Cl. D2—04

U.S. Cl. D2—282

FIG. 1

FIG. 2

FIG. 1 is a front and side perspective view of a knitted slipper showing my new design;

FIG. 2 is an opposite side rear perspective view thereof with the tassel raised.

I claim:

The ornamental design for a knitted slipper, as shown and described.
